UNITED STATES PATENT OFFICE

CHARLES A. MARSLAND, OF NEW YORK, N. Y., ASSIGNEE TO THE BALTIMORE ENAMEL & NOVELTY COMPANY, OF BALTIMORE CITY, MARYLAND

SIGN

Application filed June 3, 1929. Serial No. 368,136.

This invention relates to new and useful improvements in signs, and particularly to signs known as "drum" signs.

These signs are usually formed from sheet metal, elongated, and concavo-convex in cross section, with a suitable legend formed on the convex face. A solid wooden block, a wooden or metal frame, or the like, has been provided, on which the metal sheet is secured by means of bolts or screws, such frame being first secured to that portion of a building where the sign is to be displayed. These signs usually had the raw marginal edges exposed, and it required a number of fasteners to attach the same to the frame.

One object of the present invention is to provide a sign of this character wherein great rigidity is produced, without the use of large frames, or the use of a large amount of wood, thereby greatly reducing the cost of the sign.

Another object is to provide a sign of this character which is of such construction that the minimum number of fastening devices is required to attach the sign to the desired place on a building.

Another object is to provide a sign of this character wherein the metal portion is attached to the supporting frame, and the supporting frame attached to the proper point, by the same fastening devices, thereby economizing in fastening devices, and simplifying the hanging of the sign.

Other objects and advantages will be apparent from the following description when taken in connection with the accompanying drawing.

In the drawing:

Figure 1 is a front elevation of a sign made in accordance with the present invention, in operative position.

Figure 2 is an enlarged rear elevation of the same.

Figure 3 is a transverse sectional view on the line 3—3 of Figure 1, partly in section.

Referring particularly to the accompany-

ing drawing, 10 represents a metal sheet of proper size which is concavo-convex in cross section, and having its side edges bent inwardly, as shown at 11. Disposed against the concave face of the member 10, at each end thereof, is a wooden block 12, the outer face of which is curved, as at 13, to snugly fit the concave face of the metal sheet, said block having terminal angles 14 which snugly fit within the angles formed between the body 50 of the sheet and the side edges 11. A V-shaped cut 15 is made in the rear face of each of the wooden blocks 12. Formed through the center of the upper and lower ends of the metal sheet 10 is an opening 16, and a similar opening 17 is formed through the center of each block in alignment with the opening 16, for the passage of the screw 18, which is driven into the support 19, on which the sign 55 is hung.

Thus, when the sign is to be hung on a door frame, or the wooden corner of a show window of a store, it is only necessary to place the sign in such position that the door frame or the window frame enters the V-shaped cuts of the wooden blocks 12, and then drive the two screws into such door or window frame, through the openings of the metal sign and the wooden blocks. It will be noted that the metal portion of the sign is attached 70 to the wooden blocks at two points, only, and that the means by which they are fastened 75 are the same means which secure the sign to its support.

What is claimed is:

1. A sign including a metal sheet concavo-convex in cross section, opposite sides of the sheet being provided with flanges extending inwardly at angles to the body of the sheet, and blocks substantially of the form of segments of a circle having their convex faces fitted against the concave face of the sheet and having their angular ends snugly seated within the said angles of the body and flanges. 85

2. A sign including a metal sheet concavo- 90

convex in cross section, opposite sides of the sheet being provided with flanges extending inwardly at acute angles to the body of the sheet, and blocks of the form of segments of a circle having their convex faces fitted against the concave face of the sheet and having their angular ends snugly seated within the acute angles of the body and flanges, the sheet and blocks having alining 10 fastening receiving openings.

In testimony whereof, I affix my signature.
CHARLES A. MARSLAND.
